(57) CLAIM

The ornamental design for an undershirt with underarm gusset, as shown and described.

DESCRIPTION

FIG. 1 is a perspective view of the underarm gusset of the present design positioned on a body;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line portions of the drawings depict environmental subject matter only and form no part of the claimed design.

1 Claim, 7 Drawing Sheets
